METHOD AND APPARATUS FOR ROLLING

Alonzo B. Montgomery, Youngstown, Ohio, assignor to The Cold Metal Process Company, Youngstown, Ohio, a corporation of Ohio

Application January 19, 1934, Serial No. 707,401

5 Claims. (Cl. 80—60)

My invention relates to the rolling of metal and particularly to long lengths of thin sheet metal, such as strip.

In the U. S. patent granted July 18, 1933 to Keeney, et al., No. 1,918,968, there is disclosed a four-high reversing mill with heating furnaces on opposite sides thereof for hot rolling strip. My invention is concerned chiefly with improvements upon the method and apparatus disclosed 10 in said patent.

For certain classes of product, it is desirable to provide a finish on the hot strip superior to that which can be obtained with the mill shown in the Keeney patent, in which the entire reduction from the slab to the strip is effected by the same rolls. In order to roll a slab in the Keeney mill, the slab must be highly heated, specifically, above the temperature at which free scaling occurs. The presence of the scale on the slab 15 roughens the rolls and precludes the obtaining of a high finish on the hot strip of final gauge. The rolls thus wear rapidly and require frequent changing. The output, furthermore, is limited because of the fact that the slabbing operation is necessarily slow due to the frequent reversals of 20 the mill, and full advantage of the capacity of the four-high mill for high-speed operation is realized only during a portion of the operating cycle, namely, during the rolling with coiling.

30 In rolling strip from slabs on the Keeney mill, in addition, the effect of the edging rolls used to control and assist in the removal of scale, is to cause the production of ears or projections at the corners of the slab as it is reduced to strip form. These ears make it difficult to direct material on to the coiler for the continuation of the hot rolling.

In accordance with my invention, I take a slab after it has been properly heated in a suitable 40 furnace and subject it to repeated passes through a universal mill to elongate it considerably without materially increasing its width. The ends of the piece are then sheared off to remove the ears projecting therefrom. The material is then 45 passed into another reversing mill, e. g., that of the Keeney patent, with heating furnaces on opposite sides thereof, where it is subjected to further rolling with coiling between passes. After the material has been reduced sufficiently in the 50 four-high mill, it is wound on a final coiler.

For a complete understanding of the invention, reference is made to the accompanying drawing illustrating diagrammatically a present preferred embodiment of the invention and the method of 55 its practice.

Referring in detail to the drawing, furnaces 10 are provided for heating slabs for delivery to a universal mill 11. As is well known, the universal mill is a two-high reversing mill with one or more pairs of vertical rolls or edgers. A roll table 12 extends from the furnaces to the mill. A slab shear 13 is positioned at a suitable distance ahead of the mill 11 with a connecting roll table 14 therebetween.

A second reversing mill 15, preferably but not 10 necessarily a four-high mill, has coil-heating furnaces 16 and 17 on opposite sides thereof, and pinch rolls 18 between the coil furnaces and the mill rolls. A roll table 19 connects the shear 13 and the mill 15. A crop conveyor 20 and a slab 15 conveyor 21, with an associated pusher 22, extends laterally from the table 19. A hot strip coiler 24 is located beyond the mill 15. Roll tables 25 connect the mill 15 and the coiler 24.

The operation of the apparatus above enumerated 20 is to perform the method of my invention, may be described briefly as follows: The slabs are fed into the furnaces 10 to be heated prior to rolling in the mill 11. The slabs are initially 2" to 14" thick and of suitable width and length to 25 provide the desired dimensions of finished hot strip. The heated slabs are passed back and forth through the universal mill 11, which effects a slabbing operation, until the slab is reduced to a thickness of $\frac{1}{2}$ " or less, with a corresponding elongation, and is cooled to a point where free scaling substantially ceases. The partially reduced slab is then forwarded to the four-high mill 15. The ends of the hot slab, however, are sheared off by the shear 13 before 30 the piece arrives at the coiling mill.

Generally, I prefer to perform all slabbing operations on the mill 11 and thereby reduce the material to a gauge suitable for coiling before advancing it to the mill 15. The material enters the 40 mill 15 while still hot and is coiled up in the coil-heating furnace 17 after the first pass through the mill. On the next pass, the material is coiled in the heating furnace 16. This cycle is repeated and the partially reduced slab is gradually 45 elongated to strip form, the heat lost from the strip by radiation, and otherwise, being supplied during the interval it dwells in the coil-heating furnaces.

When the strip has been reduced to final 50 gauge, say .065", it is advanced from the mill 15 in the flat form along the table 25 toward the final coiler 24. After the strip has been coiled on the coiler 24, and cooled, it is ready for shipment 55

or further processing, for example, by cold rolling.

While I have stated that it is preferable to perform all the slabbing operations on the mill 11, 5 it is possible that in certain cases it may be desirable to effect some reduction of the material in the flat on the mill 15.

It will be apparent to those skilled in the art that the invention described is characterized by numerous advantages over the practice and apparatus heretofore employed. In the first place, 10 a higher finish can be obtained than by using the four-high mill for both slabbing and coiling operations. Since the slabbing operation is confined to the universal mill, by far the greatest portion of free scaling has occurred before the material reaches the four-high mill, at which time it is characterized by a tight, thin layer of oxide which adheres to the strip throughout 15 the further rolling. Excessive accumulation of scale in the four-high mill is thus prevented, as well as the resulting injury to the surface of the working rolls. The output of the four-high mill is increased from 25 to 30%, furthermore, 20 because of the fact that it is operating at high speeds a greater portion of the time than when slabbing operations are effected therein. The high speeds of which the mill is capable, of course, can best be taken advantage of when 25 rolling the longer lengths. The reduction in the wear on the rolls of the four-high mill makes it unnecessary to change rolls as frequently as has heretofore been the case. The shearing of 30 the ends of the partly reduced slab before rolling, greatly facilitates the entry of the material into the furnace reels, making the operation of the mill 15 more efficient and avoiding the delays and loss of material incident to repeated efforts to cause the end of the piece to engage 35 the reel. While I have described the cropping of the ends of the slab as taking place between the slabbing and the rolling with coiling, it is obvious that where some slabbing is done on the four-high mill, the shearing may be performed after such final slabbing. 40

Although I have illustrated and described but a single preferred embodiment of my invention with certain possible modifications thereof, it will be understood that numerous changes in the 45 apparatus and practice disclosed may be made without departing from the spirit of my invention or the scope of the appended claims.

I claim:

1. In a method of rolling metal strip, the 50 steps consisting in supplying to a roughing mill a heated slab-like body which is too thick for coiling, rolling the body in the roughing mill

until it is substantially thin enough to permit of coiling, but maintaining the thinned body in the flat state, and, in the same heat, feeding the thinned body to a reversing mill, subjecting it to successive passes therein to reduce it to a desired strip thickness, and coiling it between 5 passes in the reversing mill.

2. In a method of rolling metal strip, the steps consisting in supplying to a roughing mill a heated slab-like body which is too thick for coiling, rolling the body in the roughing mill until it is substantially thin enough to permit of coiling, but maintaining the thinned body in the flat state, trueing the edges in said mill, and, in the same heat, feeding the thinned body 15 to a reversing mill, subjecting it to successive passes therein to reduce it to a desired strip thickness, and coiling it between passes in the reversing mill.

3. In a method of rolling metal strip, the steps consisting in supplying to a roughing mill a heated slab-like body which is too thick for coiling, rolling the body back and forth in the roughing mill until it is substantially thin enough to permit of coiling, but maintaining the thinned body 20 in the flat state, and, in the same heat, feeding the thinned body to a reversing mill, subjecting it to successive passes therein to reduce it to a desired strip thickness, and coiling it between passes in the reversing mill. 30

4. In a method of rolling metal strip, the steps consisting in supplying to a roughing mill a heated slab-like body which is too thick for coiling, rolling the body in the roughing mill until the body cools to a temperature below that 35 at which free scale forms, and until it is substantially thin enough to permit of coiling, but maintaining the thinned body in the flat state, and, in the same heat, feeding the thinned body to a reversing mill, subjecting it to successive passes 40 therein to reduce it to a desired strip thickness, and coiling it between passes in the reversing mill.

5. In a method of rolling metal strip, the steps consisting in supplying to a roughing mill a heated slab-like body which is too thick for coiling, rolling the body in the roughing mill until it is substantially thin enough to permit of coiling, but maintaining the thinned body in the flat state, and, in the same heat, feeding the thinned body 45 to a reversing mill after cropping at least one end of the thinned body to facilitate its entry into said reversing mill, subjecting it to successive passes therein to reduce it to a desired strip thickness, and coiling it between 50 passes in the reversing mill. 55

ALONZO B. MONTGOMERY.
